The ornamental design for an absolute pressure transducer, as shown and described.

DESCRIPTION

FIG. 1 is a top perspective view of the present invention;

FIG. 2 is a bottom view of the present invention;

FIG. 3 is a bottom perspective view of the present invention;

FIG. 4 is a top view of the present invention;

FIG. 5 is an end view of the present invention, the opposite end being the same; and,

FIG. 6 is a side view of the present invention, the opposite end being the same.

FIG. 1

FIG. 2

FIG. 3

FIG. 4

FIG. 5

FIG. 6
